pling portion is provided with a through-hole, and a pair of connection portions which face with each other across the through-hole and which connects a space between the T-shaped cores.

REACTOR

**CROSS-REFERENCE TO RELATED
APPLICATION**

This is a National Phase Application filed under 35 U.S.C. 371 as a national stage of PCT/JP2019/001154, filed Jan. 16, 2019, an application claiming the benefit of Japanese Application No. 2018-005989, filed Jan. 17, 2018, the content of each of which is hereby incorporated by reference in its entirety.

FIELD OF THE INVENTION

The present disclosure relates to a reactor.

BACKGROUND

A reactor is used for various electrical apparatuses, and includes a reactor main body that includes a core and a coil wound around the circumference of the core, and a casing that houses therein the reactor main body. The core is often formed by combining a plurality of partial cores, and in this case, a magnetic gap may be formed between the partial cores. This gap may be formed of an air gap, or a resin material, such as a spacer, may be present therebetween.

Problem to be Solved by the Invention

In order to ensure the insulation between the core and the coil, all or a part of the core is embedded in the resin material by molding. In this case, in the magnetic gap between the partial cores, since no core is present and is solid that is entirely filled by the resin material, the resin material becomes thick. However, the resin material near the solid portion in the gap is likely to be deformed by so-called sink mark. That is, when the resin material which covers the surroundings of a protruding portion of the core adjacent to the solid portion becomes thin due to shrinkage caused when the resin material becomes a low-temperature and cured state from a high-temperature state with fluidity, bend and concavity are caused, and a change such as the partial cores being displaced from the proper positions relative to each other occurs.

In contrast, when the resin material is thin, since the strength of such a portion is small, a deformation is likely to occur, and the relative positions of the partial cores become unstable. When the positions of the partial cores change, a distance between the core and the coil and the distance between the coils change, a mutual contact may occur such that the insulation would not be ensured.

The present disclosure has been made in order to address the foregoing technical problems, and an objective is to provide a reactor in which a deformation of a resin material in a gap between partial cores is suppressed.

SUMMARY OF THE INVENTION

A reactor according to the present disclosure includes: a core which includes at least a pair of partial cores disposed via a gap; a coil attached to a part of the core; and a core molding member which is formed integrally by a resin material and which covers the pair of partial cores,

2

in which:

the core molding member includes a coupling portion which is provided between the pair of partial cores at a location corresponding to the gap; and

5 the coupling portion includes a through-hole, and a pair of connection portions which face with each other across the through-hole and which connects a space between the pair of partial cores.

According to the present disclosure, a reactor in which a 10 deformation of a resin material in a gap between partial cores is suppressed is provided.

BRIEF DESCRIPTION OF THE DRAWINGS

15 FIG. 1 is a plan view of a reactor according to an embodiment;

FIG. 2 is a front side perspective view of the reactor according to the embodiment;

20 FIG. 3 is an exploded perspective view illustrating a reactor main body and a casing;

FIG. 4 is an exploded perspective view of the reactor main body;

FIG. 5 is a perspective view of a core casing in which a T-shaped core is embedded;

25 FIG. 6 is a plan view of FIG. 5;

FIG. 7 is a cross-sectional view taken along a line B-B' in FIG. 5 and FIG. 6;

FIG. 8 is a cross-sectional view taken along a line A-A' in FIG. 1;

30 FIG. 9 is a plan view illustrating an example core casing that includes a thick coupling portion;

FIG. 10 is a plan view illustrating an example core casing that includes a thin coupling portion;

FIG. 11 is a perspective view illustrating another aspect of 35 the coupling portion;

FIG. 12 is a perspective view illustrating another aspect of the coupling portion; and

FIGS. 13A and 13B are each a plan view illustrating another example structure of the core.

40 FIG. 14 is an exploded perspective view illustrating an example in which one end portion of the through-hole is enlarged.

FIG. 15(A) is a cross-sectional view taken along a line B-B' in FIG. 14 in which one end of the through-hole is enlarged, FIG. 15(B) is a cross-sectional view illustrating an example in which both end portions of the through-hole is enlarged, and FIG. 15(C) is a cross-sectional view illustrating an example in which an interior of the through-hole is inclined.

50 FIG. 16 is a perspective view illustrating an example in which a restriction portion is provided to the core molding member.

FIG. 17 is a side view of FIG. 16.

FIG. 18 is a cross-sectional view illustrating an example 55 in which a connection hole is formed in the connection portion.

**DETAILED DESCRIPTION OF THE
EMBODIMENTS**

60 A reactor according to an embodiment will be described with reference to the accompanying drawings. In this specification, a direction along Z-axis in FIG. 1 will be defined as an “upper” side, and the opposite side will be defined as a “lower” side. In the description of structures of each component, the “lower” side will be also referred to as a “bottom”. The direction along Z-axis is a height direction of

the reactor. Moreover, a direction along X-axis in FIG. 1 and an opposite direction thereto will be defined as a “widthwise direction”, and a direction along Y-axis and the opposite direction thereto will be defined as a “depthwise direction”. A plane defined by the “widthwise direction” and the “depthwise direction” will be defined as a “horizontal direction”. Those directions are notations to describe the positional relationship among each components of the reactor, and are not intended to limit the positional relationship and the direction when the reactor is installed on an object where the reactor is to be installed.

[Structure]

As illustrated in a FIG. 1 that is a plan view and FIG. 2 that is a front side perspective view, a reactor 100 includes a reactor main body 1, a casing 3, a bus bar 4, and a terminal stage 5.

[Reactor Main Body]

As illustrated in FIG. 1 that is a plan view and FIG. 3 that is an exploded perspective view, the reactor main body 1 according to the present embodiment is formed in a substantially rectangular shape with rounded corners as a whole which has a pair of long sides and a pair of short sides, in a plan view. A rectangular shape with rounded corners is a rectangle which has rounded corners. As illustrated in FIG. 4 that is an exploded perspective view, the reactor main body 1 includes a core 10 and a coil 20.

[Core]

The core 10 is a magnetic substance, such as a powder magnetic core, a ferrite magnetic core, or a laminated steel plate, and the interior thereof serves as a path for magnetic fluxes produced by the coil 20 to be described later to form a magnetic circuit. The core 10 of the present embodiment includes at least a pair of partial cores disposed via a gap. More specifically, as illustrated in FIG. 4, the core 10 includes, as the partial cores, two I-shaped cores 11a and 11b and two T-shaped cores 12a and 12b. The I-shaped cores 11a and 11b are each in a substantially cuboid shape. The T-shaped cores 12a and 12b are each in a substantially T-shape by having respective center protrusions Pa and Pb formed on respective side surfaces facing each other at portions in the substantially cuboid. The core 10 forms an annular core by butting and bonding one surfaces of the I-shaped cores 11a and 11b, and both end portions of the T-shaped cores 12a and 12b via an unillustrated adhesive. More specifically, in the present embodiment, since the center protrusions Pa and Pb are located inwardly relative to the annular shape, the core is formed in a substantially 0 shape as a whole.

The one surfaces of the I-shaped cores 11a and 11b and both end portions of the T-shaped cores 12a and 12b may be in direct contact and butted without an adhesive, or may have a magnetic gap therebetween. Such a magnetic gap may be formed by providing a spacer or may be formed by an air gap.

Furthermore, according to the present embodiment, a core molding member 6, which is formed of a resin material and which covers the partial cores, is provided. The core molding member 6 includes core casings 61a, 61b, and 62. The core casing 61a is an insulation resin mold component that houses therein the I-shaped core 11a. The core casing 61b is an insulation resin mold component that houses therein the I-shaped core 11b. The core casing 62 is an insulation resin mold component that houses therein the T-shaped cores 12a and 12b. The core casings 61a, 61b, and 62 are present between the core 10 and the coil 20 to ensure insulation.

The core casing 61a is integrally formed by filling and curing resin material with the I-shaped core 11a set in a

mold. The core casing 61b is integrally formed by filling and curing resin material with the I-shaped core 11b set in a mold. The core casing 62 is integrally formed by filling and curing resin material with the T-shaped cores 12a and 12b set in a mold. The wordings “formed integrally” means that the partial cores are embedded in the resin material. In addition, the wordings “formed integrally” involve a case in which the plurality of partial cores is separately embedded in the resin material and then combined, and a case in which the plurality of partial cores is embedded collectively so that it is continuously formed without a seam.

However, openings are provided in the core casings 61a and 61b that cover the I-shaped cores 11a and 11b, respectively, at portions corresponding to joined surfaces of the I-shaped cores 11a and 11b relative to the T-shaped cores 12a and 12b. Openings are provided in the core casing 62 that covers the T-shaped cores 12a and 12b at portions corresponding to joined surfaces of the T-shaped cores 12a and 12b relative to the I-shaped cores 11a and 11b. Engaging portions that are to be engaged with each other when the core 10 is assembled into substantially 0 shape are formed in those openings of the core casings 61a, 61b, and 62.

As illustrated in FIGS. 3 and 4, attaching portions 15 for fixing to the casing 3 are formed on the outer surfaces of these core casing 61a and 61b. The attaching portion 15 is a tabular piece protruding outwardly, and an attaching hole 16 in which a bolt B is inserted is formed. The bolt B is a fastener which has a screw. Two attaching portions 15 are formed on both ends of the I-shaped core casing 61a, and one attaching portion 15 is formed on the center of the I-shaped core casing 61b. These attaching portions 15 are formed together with the molding of the core casings 61a and 61b.

The pair of T-shaped cores 12a and T-shaped core 12b which are the partial cores are disposed via a gap G. That is, an end surface of the center protrusion Pa of the T-shaped core 12a and an end surface of the center protrusion Pb of the T-shaped core 12b face with each other via the magnetic gap G which is an air gap. The core casing 62 that is the core molding member 6 which covers the T-shaped cores 12a and 12b has a coupling portion 621 at a location corresponding to the gap G between the T-shaped cores 12b and 12b. Therefore, the core casing 62 is formed in a substantially H-shape as a whole in a planar view. Moreover, the coupling portion 621 is disposed at the inner-circumference side of the annular core 10.

As illustrated in FIG. 5 that is a perspective view and FIG. 6 that is a plan view, the coupling portion 621 includes a through-hole 622, and connection portions 623 and 624. The through-hole 622 is a hole penetrating in the lengthwise direction of the T-shaped cores 12a and 12b, that is, in parallel with the winding direction of the coil 20. The through-hole 622 is in a rectangular shape that has a long cross-section in the height direction.

The connection portions 623 and 624 face with each other across the through-hole 622, and connect a space between the T-shaped core 12a and the T-shaped core 12b. In the present embodiment, a direction along the x-axis direction, that is, a direction in parallel with the lengthwise direction of the I-shaped cores 11a and 11b, and a direction orthogonal to the lengthwise direction of the T-shaped cores 12a and 12b will be defined as the connection direction. It is preferable that the clearance between the edges of the connection portions 623 and 624 facing with each other, that is, a length between an upper edge of the connection portion 623 and a lower edge of the connection portion 624 in the height direction is equal to or greater than the thickness of the

T-shaped cores 12a and 12b in the height direction. The connection portion 623 is bridged across the upper portions of the T-shaped core 12a and T-shaped core 12b. The connection portion 623 includes an opening 625. The opening 625 is a hole in communication with the through-hole 622. The opening 625 of the present embodiment has a rectangular shape. Therefore, by providing the opening 625 that is in communication with the through-hole 622, the connection portion 623 includes a pair of opposing connection portions 623a and 623b which face with each other via a clearance in a direction orthogonal to the connection direction, that is, a direction along the y-axis direction. The opposing connection portions 623a and 623b are each tabular, and the planar direction thereof is the height direction (a direction along the z-axis direction). That is, the connection portion 623 includes tabular portions that face with each other.

The connection portion 624 is bridged across the lower portions of the T-shaped core 12a and T-shaped core 12b. The connection portion 624 has a tabular portion. The tabular portion has the planar direction in the horizontal direction. That is, the connection portion 623 and the connection portion 624 have respective tabular portions that face with each other in the direction orthogonal to each other. The connection portion 624 is formed to be equal to or smaller than the width of the opening 625 at a location that face the opening 625s. That is, the connection portion 624 is disposed at an opposing location between the opposing connection portions 623a and 623b, and is formed with the width equal to or smaller than the clearance between the opposing connection portions 623a and 623b. The term "width" in this case is a length in the lengthwise direction of the T-shaped cores 12a and 12b, and is different from the widthwise direction of the reactor 100 and the reactor main body 1. According to the present embodiment, as illustrated in FIG. 7 that is a cross-sectional view taken along a line B-B' in FIG. 5 and in FIG. 6, the opening 625 and the connection portion 624 located between the opposing connection portions 623a and 623b face with each other in the vertical direction across the through-hole 622, and a width h1 of the opening 625 and a width h2 of the connection portion 624 are substantially consistent with each other. Therefore, the opening 625, through-hole 622, and connection portion 624 of the coupling portion 621 can be formed by upper and lower mold M1 and M2 without applying a slide.

The core casing 62 further includes a wall portion 626 and an inclined portion 627. The wall portion 626 is a pair of walls standing upright at locations that face with each other across the opening 625. More specifically, the wall portion 626 is a pair of tabular pieces 626a and 626b, and provided in parallel with each other in the orthogonal direction to the T-shaped cores 12a and 12b.

The inclined portion 627 is formed in such a way that the thickness of the resin material becomes thin toward the opening 625. More specifically, the inclined portion 627 has the resin material that becomes thicker as becoming a part from the opening 625, and has the resin material that becomes thinner as becoming close to the opening 625, and is an inclined surface relative to the horizontal direction. The inclined portion 627 is provided between the tabular pieces 626a and 626b, and includes a flat inclined surface 627a at the T-shaped-core-12a side, and a flat inclined surface 627b at the T-shaped-core-12b side. The tabular pieces 626a and 626b have respective portions continuous from the opposing connection portions 623a and 623b, respectively. As illustrated in FIG. 8 that is a cross-sectional view taken along a

line A-A' in FIG. 1, the inclined surfaces 627a and 627b have a vertical cross-section that is in a substantially V-shape.

[Coil]

5 The coil 20 is a conductive member attached to the core 10. As illustrated in FIG. 4 that is an exploded perspective view, the coil 20 according to the present embodiment is an edgewise coil of a rectangular flat wire which has an insulation coating. However, the winding material of the coil 10 20 and the way of winding are not limited to any particular types, and other forms may be employed.

15 The coil 20 includes coupled coils 21 and 22. The coupled coil 21 forms a pair of partial coils 21a and 21b using a single conductor. The coupled coil 22 forms a pair of partial coils 22a and 22b using a single conductor.

20 The partial coils 22a and 22b are attached to the respective one ends of the T-shaped cores 12a and 12b. That is, the partial coils 22a and 22b are disposed at the I-shaped-core-11a side relative to the center protrusions Pa and Pb. The partial coils 22a and 22b are attached to the respective other ends of the T-shaped cores 12a and 12b. That is, the partial coils 22a and 22b are disposed at the I-shaped-core-11b side relative to the center protrusions Pa and Pb.

25 Winding start and winding termination end portions 21c and 21d of the coupled coil 21 drawn out from the wound portion and winding start and winding termination end portions 22c and 22d of the coupled coil 22 drawn out from the wound portion are respectively drawn outwardly relative to the reactor main body 1. More specifically, the end portions 21c and 21d extend along a long-side direction of the reactor main body 1, and protrude from the one short-side. The end portions 22c and 22d extend along the long-side direction of the reactor main body 1, and protrude from the other short-side.

30 35 The coupled coil 21 and the coupled coil 22 are wound in such a way that magnetic fluxes respectively produced are in opposite directions to each other. The wordings to wind in such a way that DC magnetic fluxes are in opposite directions to each other involve a case in which the winding directions are inverted but currents in the same directions are caused to flow, and also a case in which the winding direction is consistent but currents in the opposite directions are caused to flow.

[Casing]

40 45 As illustrated in FIG. 3 that is an exploded perspective view, the casing 3 houses therein the reactor main body 1, and has a portion where an opening 33 is formed. It is preferable that the casing 3 should be formed of a material which has a high thermal conductivity and which achieves a magnetic shield effect. For example, a metal, such as aluminum, magnesium or an alloy thereof is applicable. Moreover, it is not always necessary that the casing 3 is formed of a metal, and a resin that has an excellent thermal conductivity or a structure in which a metal heat dissipation plate is partially embedded in such a resin is applicable. Moreover, a magnetic substance is applicable to the entire casing 3 or a part of the casing. The magnetic substance has a higher magnetic shield effect than that of a metal like aluminum.

50 55 60 The casing 3 includes a support 31 and a wall 32. The support 31 is supported by an unillustrated installation surface. In the present embodiment, the support 31 is a flat-plate member in a substantially rectangular shape. Concavities and convexities along the reactor main body 1 are formed in the surface of the support 31 at a side where the reactor main body 1 is housed. However, a clearance is provided between the reactor main body 1 and the support

31. Moreover, fastening holes 31a for fastening to the installation surface are formed in the four corners of the support 31 and near respective centers of the long sides thereof.

The wall 32 is provided on the support 31 so as to stand upright, and surrounds the circumference of the reactor main body 1. The wall 32 forms the opening 33 at the opposite side to the support 31. More specifically, the wall 32 includes a pair of side walls 321 and 322 in the long-side direction of the reactor main body 1, and a pair of side walls 323 and 324 in the short-side direction. The space surrounded by the surfaces of the support 31 and of the wall 32 facing the reactor main body 1 becomes a housing space for the reactor main body 1.

The opening 33 is an opened portion formed in the wall 32 at the opposite side to the support 31. In the present embodiment, the upper portion of the casing 3 is opened by the opening 33, and apart of the reactor main body 1 protrudes from the casing 3 via such an opening. That is, since the upper edge of the wall 32 is lower than the height of the core 10, with the reactor main body 1 being housed, the respective upper portions of the coil 20 and core casings 61a, 61b, and 62 protrude from the opening 33. In the present embodiment, the upper half of the reactor main body 1 protrudes from the edge of the opening 33.

The three attachment holes 32a are formed in the wall 32 at positions corresponding to the attaching holes 16 of the core casings 61a and 61b. A screw thread is cut in these attachment holes 32a. Formed between the reactor main body 1 and the support 31 of the casing 3 is the space as described above. Moreover, in order to attach the terminal stage 5, attachment holes 32b and a pin hole 32c are provided in the casing 3. A screw thread is cut in the attachment holes 32b.

[Bus Bar]

The bus bar 4 is a conductive body electrically connected to the coil 20. The bus bar 4 is provided between the coil 20 and an unillustrated external device like an external power supply, and electrically connects both to each other. The bus bar 4 is a thin elongated bandlike body, and example materials thereof are copper, aluminum, etc.

In the embodiment, as illustrated in FIGS. 1 and 2, three bus bars 41, 42, and 43 are adopted. The bus bars 41 and 43 include respective body portions 41a and 43a in a bandlike shape along the edge of the opening 33 of the casing 3, i.e., the upper edges of the side walls 321 and 322. One end of the bus bar 41 is a connection portion 411 connected to the end portion 21c of the coupled coil 21 where the insulation coating is peeled by, for example, welding. The other end of the bus bar 41 is branched into two pieces. One branched end is a terminal 412 for connection to an external device. A terminal hole 412a is formed in the terminal 412. The other branched end is a connection portion 413 connected to the end portion 22c of the coupled coil 22 where the insulation coating is peeled by, for example, welding. Hence, the terminal 412 forms a common input terminal for the coupled coils 21 and 22.

One end of the bus bar 42 is a connection portion 421 connected to the end portion 22d of the coupled coil 22 where the insulation coating is peeled by, for example, welding. The other end of the bus bar 42 is a terminal 422 for connection to an external device. A terminal hole 422a is formed in the terminal 422.

One end of the bus bar 43 is a connection portion 431 connected to the end portion 21d of the coupled coil 21 where the insulation coating is peeled by, for example, welding. The other end of the bus bar 43 is a terminal 432

for connection to an external device. A terminal hole 432a is formed in the terminal 432.

[Terminal Stage]

As illustrated in FIG. 1, the terminal stage 5 is a body that supports electric connection portion between the bus bar 4 and the exterior. In the present embodiment, a terminal stage 5A and a terminal stage 5B are provided separately and corresponding to the side faces of the casing 3 that face with each other.

The terminal stages 5A and 5B are entirely formed of a resin material. The terminal stages 5A and 5B include stage portions 51A and 51B and extended portions 52A and 52B, respectively. That is, the terminal stage 5A is formed of a resin material integrally so as to include the stage portion 51A and the extended portion 52A, and the terminal stage 5B is formed of a resin material integrally so as to include the stage portion 51B and the extended portion 52B. The wordings formed integrally involve a case in which both portions are formed separately and then joined together, and a case in which those portions are continuously formed without a seam.

An example resin material applied to form the terminal stages 5A and 5B is an insulation material. For example, polyphenylene sulfide (PPS), an unsaturated polyester-based resin, an urethane resin, an epoxy resin, bulk molding compound (BMP), and polybutylene terephthalate (PBT), etc., are applicable as the resin material.

The stage portions 51A and 51B support the respective terminals 412, 422 and 432 of the bus bars 41, 42 and 43. Terminal holes 51a corresponding to the respective terminal holes 412a, 422a and 432a of the terminals 412, 422 and 432 are formed in the stage portions 51A and 51B. Although it is not illustrated, a nut is embedded in the lower portion of the terminal hole 51a so as to be coaxial with the terminal hole 51a. Moreover, attaching holes 51b are provided in the stage portion 51B at locations corresponding to the attachment holes 32b of the casing 3. Furthermore, a space between the connection portion 421 of the bus bar 42 and the terminal 422 is embedded in the stage portion 51B.

The extended portions 52A and 52B are each a member in which a part of the body portion 41a and 43a of the bus bar 41 and 43 is embedded and which is provided along the edge of the opening 33. The extended portions 52A and 52B according to the present embodiment are mounted at the opposite side of the wall 32 to the support 31 so as to be extended above the wall 32. The extended portion 52A is extended along the upper edge of the side wall 321 from the side wall 324 at the one short-side of the casing 3. The extended portion 52B is extended along the upper edge of the side wall 322 from the side wall 324 at the one short-side of the casing 3. Attaching holes 521 are formed in the above described extended portions 52A and 52B at locations corresponding the plurality of attachment holes 32b of the casing 3.

[Placement of Reactor Main Body in Casing and Filling by Filler]

The reactor main body 1 employs the structure as follows by combining the core 10 and the coil 20. That is, the T-shaped cores 12a and 12b embedded in the core casing 62 are fitted in the coupled coils 21 and 22 that have been wound beforehand, and the joined surfaces of the T-shaped cores 12a and 12b, and the joined surfaces of the I-shaped cores 11a and 11b embedded in the core casings 61a and 61b are respectively bonded by an adhesive. Moreover, the engaging portions of the core casings 61a, 61b, and 62 are engaged with each other.

Such a reactor main body 1 is fastened to the casing 3 by aligning the respective attaching holes 16 of the core casings 61a and 61b to the respective attachment holes 32a of the casing 3 and inserting and tightening the respective bolts B. The coil 20 of the reactor main body 1 housed in the casing 3 has the winding axial direction of the wound portion disposed in parallel with the edge of the opening 33 of the casing 3, i.e., the wall 32. According to the present embodiment, such a winding axial direction is disposed in parallel with the side walls 321 and 322 in the long-side direction of the reactor main body 1.

The terminal stages 5A and 5B are mounted on the casing 3 in such a way that the attaching holes 51b and 521 is aligned with the attachment hole 32 of the casing 3. Moreover, by inserting and tightening the respective bolts B in the attaching holes 51b and 521, the terminal stages 5A and 5B are fastened to the casing 3. The terminal stage 5B is mounted on the casing 3 so as to allow an unillustrated pin to be inserted in the pin hole 32c of the casing 3. Furthermore, the connection portion 421 of the bus bar 42 is connected to the end portion 22d of the coupled coil 22, and the connection portion 431 of the bus bar 42 is connected to the end portion 21d of the coupled coil 21.

A filler is filled in the internal space of the casing 3 where the reactor main body 1 is retained, and is cured. That is, as illustrated in FIG. 8 that is a cross-sectional view taken along the line A-A' in FIG. 1, a filler molded portion R formed by the cured filler is provided in the clearance filler molded portion R between the casing 3 and the reactor main body 1. An example filler is a resin which is relatively soft and which has a high thermal conductivity in view of the ensured heat dissipation performance of the reactor main body 1 and the reduction of vibration transmission to the casing 3 from the reactor main body 1.

As indicated by a white arrow in FIG. 8, the filler is dropped into the opening 625 provided in the connection portion 623 of the core casing 62, thus flowing into the casing 3. At this time, the wall portion 626 prevents the filler from flowing out to the upper portion of the coil 20. Moreover, the inclined portion 627 causes the filler to flow toward the opening 625 by the own weight. Furthermore, the filler flowing down from the opening 625 is caused, by the through-hole 622, to flow out to the bottom surface of the casing 3 and spreads under the coil 20, the core casing 62, and further the core casings 61a and 61b.

[Action and Effect]

(1) A reactor includes: a core 10 that includes the T-shaped cores 12a and 12b which are at least a pair of partial cores disposed via the gap G therebetween; the coil 20 attached to a part of the core 10; and the core casing 62 that is the core molding member 6 which is formed integrally by a resin material and which covers the T-shaped cores 12a and 12b. The core casing 62 includes the coupling portion 621 that is provided between the T-shaped cores 12a and 12b at a location corresponding to the gap G, and the coupling portion 621 is provided with the through-hole 622, and the pair of connection portions 624 which face with each other across the through-hole 622 and which connects a space between the T-shaped cores 12a and 12b.

As described above, according to the present embodiment, since the T-shaped cores 12a and 12b are collectively molded and formed as a single component, the number of steps of assembling can be reduced. Moreover, the core casing 62 integrally formed by the resin material is not thickened since a cavity by the through-hole 622 is formed at the gap G between the T-shaped cores 12a and 12b. This suppresses a sink mark due to shrinkage when the resin

material becomes a low temperature from a high temperature, and thus positional displacements of the T-shaped cores 12a and 12b are prevented. The pair of connection portions 624 across the through-hole 622 increases the rigidity in comparison with a single and thin connection portion, thereby suppressing a deformation.

For example, as illustrated in FIG. 9, if a coupling portion L1 of a core casing C1 is filled by a resin material and thickened, a deformation is likely to occur by a sink mark. Moreover, as illustrated in FIG. 10, if a coupling portion L2 of a core casing C2 is thinned, since the rigidity is insufficient, a deformation is likely to occur. When a deformation of the coupling portion L1 and L2 occurs, since the positions of the cores embedded in the core casings C1 and C2 change, the insulation is not secured in some cases since the coils wound around the displaced cores contact with each other and the coil and the casing becomes in contact with each other, etc. According to the present embodiment, as described above, a deformation of the coupling portion 621 is suppressed, the insulation is ensured.

(2) The core 10 is annular, and the coupling portion 621 is disposed at the inner-circumference side of the annular core 10. Hence, although an adverse effect of positional displacements of the core 10 and the coil 20 due to a deformation of the coupling portion 621 may applied to the entire structure, according to the present embodiment, such a deformation is suppressed, and thus such an adverse effect is prevented. For example, in the above described structure, the core molding member 6 that covers the I-shaped cores 11a and 11b and the T-shaped cores 12a and 12b is annular as a whole, and is in a substantially θ shape having the coupling portion 621 provided at the center. For this reason, since an adverse effect of a positional displacement of the core 10 and the coil 20 due to a deformation of the coupling portion 621 is applied to various portions, it is advantageous to prevent such an adverse effect. For example, due to a deformation of the coupling portion 621, the I-shaped cores 11a and 11b and the T-shaped cores 12a and 12b are not joined plane by plane, and the bonding strength becomes insufficient. Moreover, bonding in an inclined direction causes unintended gap, decreasing the characteristics like magnetism. According to the present embodiment, such insufficient bonding strength and a decrease in characteristics can be prevented.

(3) The reactor includes: the casing 3 that houses therein the reactor main body 1 which includes the core 10, the coil 20, and the core molding member 6; and the filler molded portion R formed of a filler provided between the reactor main body 1 and the casing 3. One of the pair of connection portions 624 is provided with the opening 625 in communication with the through-hole 622. Hence, when the filler is applied from the opening 625, the filler spreads well in the interior of the casing 3 via the through-hole 622, achieving a uniform filling and a filling without a pore. Note that the location where the filler is applied is not limited to the opening 625. The filler may be also applied from a space between the inner circumference wall of the casing 3 and the circumference of the reactor main body 1. However, application of the filler only from the circumference of the reactor main body 1 is not likely to cause the filler to go around the center, a further application of the filler from the opening 625 is effective.

(4) The core casing 62 includes the wall portion 626 that includes pieces standing upright at the location facing with each other across the opening 625. This prevents the filler from flowing out to the upper portion of the coil 20.

11

(5) The core casing 62 includes the inclined portion 627 formed of a resin material that becomes thin toward the opening 625. This facilitates the filler to flow toward the opening 625.

(6) One of the pair of connection portions 623 includes the pair of opposing connection portions 623a and 623b which face with each other via a clearance in the orthogonal direction to the connection direction. Accordingly, the pair of opposing connection portions 623a and 623b, and the other connection portion 623 establish at least three connection locations, achieving a firm fastening. According to the present embodiment, a firm fastening in the direction along y-axis direction and in the direction along z-axis direction is enabled.

(7) The other one of the pair of connection portions 623 is disposed between the opposing connection portions 623a and 623b so as to face with each other, and is formed by a width that is equal to or smaller than the clearance between the opposing connection portions 623a and 623b. This enables formation of the core casing 62 by the upper and lower molds M1 and M2 (see FIG. 7) without using a slide, and thus the number of steps of production and the costs thereof can be reduced.

(8) The pair of connection portions 623 includes the respective tabular portions in the direction orthogonal to each other. This suppresses a deformation in multiple directions, achieving a further firm fastening.

OTHER EMBODIMENTS

The present disclosure is not limited to the above described embodiment, and involves other embodiments indicated below. Moreover, the present disclosure also involves a form that combines the above described embodiment with all of or some of the other embodiments to be described below. Furthermore, various omissions, replacements and modifications can be made to the embodiments without departing from the scope of the present disclosure, and such modified examples are also within the scope of the present disclosure.

(1) The form of the through-hole 622 formed in the coupling portion 621 is not limited to the above described form. For example, as illustrated in FIG. 11, the through-hole may pass completely through in the lengthwise direction of the T-shaped cores 12a and 12b, i.e., the orthogonal direction to the winding direction of the coil 20. In this case, the filler can be applied from the upper opening of the coupling portion 621. Moreover, the plurality of through-holes 622 may be provided.

(2) The opening 625 may be omitted. For example, as illustrated in FIG. 12, only the through-hole 622 may be formed which passes completely through in the lengthwise direction of the T-shaped cores 12a and 12b, i.e., the winding axis direction of the coil 20, and the connection portions 623 and 624 that face with each other across the through-hole 622 may be provided.

(3) The shapes, numbers, etc., of the core 10 of the main reactor main body 1, and the coil 20 thereof, are not limited to the above examples. It is appropriate if the gap G is provided between the partial cores that form the core 10, and at least one coil 20 is provided. The shape of the partial core that forms the core 10 is not limited to the above example. For example, as illustrated in FIG. 13A, the pair of I-shaped cores 11a and 11b may be held between a pair of C-shaped cores 13a and 13b, and the gap G may be formed between the I-shaped cores 11a and 11b. Moreover, as illustrated in FIG. 13B, the pair of T-shaped cores 12a and 12b may be

12

held between the pair of C-shaped cores 13a and 13b, and the gap G may be formed between the respective center protrusions Pa and Pb of the T-shaped cores 12a and 12b. That is, regarding the partial core, any of the I-shaped cores 11a and 11b, the T-shaped cores 12a and 12b, and the C-shaped cores 13a and 13b may be combined, and the core molding member that includes the coupling portion that couples any partial cores via the gap G may be formed. Moreover, the coil 20 may employ a structure that is formed by a pair of coils 21 and 22 with a simple winding scheme. Furthermore, the coil 20 may be formed as a single coil with a single winding scheme.

(4) An enlarged portion which the cross-sectional area of the cross-sectional shape of the through hole may be provided to one of the end portion of the above through-holes. For example, a reactor according to an aspect of an embodiment may include a core which includes at least a pair of partial cores disposed via a gap, a coil attached to a part of the core, and a core molding member which is formed integrally by a resin material and which covers the pair of partial cores, in which the core molding member includes a coupling portion which is provided between the pair of partial cores at a location corresponding to the gap, the coupling portion includes a through-hole, and a pair of connection portions which face with each other across the through-hole and which connects a space between the pair of partial cores, the reactor further includes a housing which houses therein the reactor main body having core, the coil, and the core molding member, and a filler molded portion formed of a filler provided between the reactor main body and the housing, and an enlarged portion which the cross-section of the cross-sectional shape of the through-hole may be provided to one of the end portion of the through-holes. One of the pair of connection portion may also have an opening in communication with the through-hole. Furthermore, the core molding member may include a wall portion standing upright at a location facing with each other across the opening. In addition, the core molding member may include an inclined portion formed of a resin material that becomes thin toward the opening. Moreover, one of the pair of connection portion may include a pair of opposing connection portions which face with each other via a clearance in a direction orthogonal to the connection direction. The other of the pair of connection portion may be disposed at an opposing location between the opposing connection portions, and may be formed with the width equal to or smaller than the clearance between the opposing connection portions. The pair of connection portion may include a tabular portion in the direction orthogonal to each other.

That is, as illustrated in FIG. 14 and FIG. 15 which is a cross-sectional view taken along a line B-B' in FIG. 14, an enlarged portion 628, in which the cross-sectional area orthogonal to the axis in parallel with the winding direction is enlarged toward one of the end portion from the inner side of the coupling portion 621, is provided to the through-hole 622. In detail, the enlarged portion 628 is formed by an inclined surface 628a which is provided continuously at the inner surface in parallel with the axis of the through-hole 622 and which is inclined relative to the axis of the through-hole 622. This inclined surface 628a is provided across the whole circumference of one of the end portion of the through holes 622. Accordingly, as indicated by a dotted arrow in FIG. 15(A), in both end portion of the through-hole 622, the filler that has flown in from the other end portion may easily flow out via larger one of the end portions. Note that the end portion of the through-hole 622 is the end portion corre-

sponding to two facing side surface of the coupling portion 621, and is the end portion toward two regions divided by the coupling portion 621.

Here, in the casing which houses therein the reactor main body, heat-dissipation effect is improved because heat from the reactor main body is transferred to the casing via the filler. To achieve such heat-dissipation effect, it is preferable that the filler is uniformly filled between the reactor main body and the casing. Then, when the resin material is present in the magnetic gap between the partial cores, since the region between the partial cores is divided into a plurality of regions by the resin material, the filler have to be dropped to each of the plurality of regions. However, if the conductor of the coil, or other members are located in the position that covers any of the regions, the filler cannot be dropped to said region. Furthermore, when dropping the filler to each of the plurality of regions, the nozzle of the filling apparatus needs to be increased, or the process of moving common nozzle needs to be increased. To address this, the through-hole may be provided to the resin material so that the filler can flow between the plurality of regions, however, even in this case, the filler may not be uniform among each regions due to the insufficient flowing.

In detail, since the coupling portion 621 is present in the region between the T-shaped cores 12a and 12b that are the pair of partial cores, to completely fill the filler, the filler have to be dropped to two regions divided by the coupling portion 621. In the below description, one region of two regions is referred to as the first region α and the other of two regions is referred to as the second region β . However, since the conductor of the coil 20, or other members are overlapped in the position that covers either one of the first region α and the second region β , there is a case in which the filler can be dropped only from one of regions. Furthermore, there is a case in which it is hard to provide the opening 625 for flowing in the filler to the coupling portion 621 due to the position where the members are located. In addition, even in a case there is no restriction due to the dropping position, it is required to prepare a plurality of nozzles or to move one nozzle to a plurality of dropping positions.

In the present aspect, as described above, the problem that it is hard to completely fill the filler to the plurality of regions can be addressed. That is, in the present aspect, region between the pair of partial cores is divided into the first region α and the second region β by the coupling portion 621, and the enlarged portion is provided to the first region α corresponding to the through-hole 622. Accordingly, the filler dropped from the second region β flows into the first region α from the second region β via the through-hole 622, and since the enlarged portion 628 is provided on the first region α side of the through-hole 622 so that the cross-section of opening becomes large, the filler can easily flow into the first region α . Therefore, the filler can be completely filled not only in one region divided by the coupling portion 621, but also to the other region. Furthermore, since variation in height of the filler molded portion R in two regions is suppressed, the reduction in the heat-dissipation can be prevented. In addition, the contact area between the coupling portion 621 and the filler is increase by the enlarged portion 628, the heat-dissipation effect is further increased. Moreover, since the filler can be completely filled from one of the regions, the number of nozzles of filling apparatus and the number of movement of the nozzle for filling from the other region can be reduced, and the productivity is improved.

Furthermore, the enlarged portion which the cross-sectional area of the cross-sectional shape of the through-hole

may be provided to both of the end portions of the above through holes. For example, a reactor according to an aspect of an embodiment may include a core which includes at least a pair of partial cores disposed via a gap, a coil attached to 5 a part of the core, and a core molding member which is formed integrally by a resin material and which covers the pair of partial cores, in which the core molding member includes a coupling portion which is provided between the pair of partial cores at a location corresponding to the gap, 10 the coupling portion includes a through-hole, and a pair of connection portions which face with each other across the through-hole and which connects a space between the pair of partial cores, the reactor further includes a housing which houses therein the reactor main body having core, the coil, 15 and the core molding member, and a filler molded portion formed of a filler provided between the reactor main body and the housing, and an enlarged portion which the cross-section of the cross-sectional shape of the through-hole may be provided to both of the end portions of the through-holes. 20 Providing the enlarged portion to the end portions of both of the through-holes means that the enlarged portion is provided not only to one of the end portions of through-holes as the above aspect, but is also provided to the other end portion. One of the pair of connection portion of this aspect 25 may also have an opening in communication with the through-hole. Furthermore, the core molding member may include a wall portion standing upright at a location facing with each other across the opening. In addition, the core molding member may include an inclined portion formed of 30 a resin material that becomes thin toward the opening. Moreover, one of the pair of connection portion may include a pair of opposing connection portions which face with each other via a clearance in a direction orthogonal to the connection direction. The other of the pair of connection portion 35 may be disposed at an opposing location between the opposing connection portions, and may be formed with the width equal to or smaller than the clearance between the opposing connection portions. The pair of connection portion may include a tabular portion in the direction orthogonal to each other.

That is, as illustrated in cross-sectional view of FIG. 15(B), the enlarged portion 628, in which the cross-sectional area orthogonal to the axis in parallel with the winding direction is enlarged toward both of the end portion from the 45 inner side of the coupling portion 621, is provided to the through-hole 622. In detail, the enlarged portion 628 is formed by an inclined surface 628a which is provided continuously at the inner surface in parallel with the axis of of the through-hole 622 and which is inclined relative to the axis of the through-hole 622. This inclined surface 628a is provided across the whole circumference of both of the end portions of the through holes 622. Accordingly, as indicated by a dotted arrow in FIG. 15(B), since the filler may easily 50 flow in from the other end portion of the through-hole 622, the filler may further easily be completely filled in both 55 regions. Therefore, in the present aspect, the problem can be addressed similarly as the above aspect in which the enlarged portion 628 is provided to one of the end portion of the through-hole 622, and excellent effect can be obtained.

Note that the inclined surface 628a in the above aspect 60 may be provided to a part of the end portion of the through-hole 622. When the cross-sectional shape of the through-hole 522 is a rectangle, the inclined portion may be provided to one side of either of the end portion of the through-hole 622, may be provided only to two sides along z-axis, or may be provided only to two sides along x-axis. When considering that the casing 3 that is the housing is on

lower side where the gravity is applied at the time of filling the filler, it is preferable that the inclined surface **628a** is provided to at least the bottom side, that is, one horizontal side at the casing 3-side. Furthermore, in addition to one side in the casing 3-side, it is preferable that the inclined surface **628a** is provided to two side orthogonal to said one side. In addition, although the cross-sectional shape in this aspect is rectangle, the shape is not limited thereto.

Moreover, at least one inner surface of the through-hole **522** may be inclined relative to the axis of the through-hole **622**, so that the cross-sectional area of the cross-sectional shape of the through-hole **622** is enlarged toward the enlarged portion **628**. Entire inner surface of the through-hole **622** may be inclined, either one of the inner surface of the through-hole **622** may be inclined, only two inner surface along z-axis may be inclined, or only two inner surface along x-axis may be inclined. When considering that the casing 3 that is the housing is on lower side where the gravity is applied at the time of filling the filler, it is preferable that at least inner bottom surface, that is, one horizontal inner surface at the casing 3-side, that is, the housing-side is inclined. Furthermore, in addition to one inner surface in the casing 3-side, it is preferable that two surfaces orthogonal to said one surface are inclined. By inclination, the fluidity of the filler is further improved. Here, the inclination angle relative to the axis of the through-hole **622** and the inclination angle relative to the axis of the inclined surface **628a** forming the enlarged portion **628** may be the different or the same. When the inclination angles are the same, the inner surface of the through-hole **622** and the inclined surface **628a** is continuous as illustrated in FIG. 15(C), and in this case, the end portion of the through-hole **622** and the region nearby may be regarded as the inclined surface **628a** corresponding to the enlarged portion **628**. By such a structure, the configuration of the molding may be simplified. Note that inclined portion for improving the fluidity of the filler may be provided to the end portion of the above opening **625**, to the inner surface of the above opening **625**, etc., to further improve the fluidity of the filler into the through-hole **622** and the plurality of regions.

(5) A restriction portion to restrict the clearance between the partial coils may be provided to the above core molding member. For example, a reactor according to an aspect of an embodiment may include a core which includes at least a pair of partial cores disposed via a gap, a coil attached to a part of the core, and a core molding member which is formed integrally by a resin material and which covers the pair of partial cores, in which the core molding member includes a coupling portion which is provided between the pair of partial cores at a location corresponding to the gap, the coupling portion includes a through-hole, and a pair of connection portions which face with each other across the through-hole and which connects a space between the pair of partial cores, the reactor further includes a housing which houses therein the reactor main body having core, the coil, and the core molding member, and a filler molded portion formed of a filler provided between the reactor main body and the housing, and the coil includes a pair of partial coils attached across the coupling portion, and the reactor includes a restriction portion to restrict the clearance between the partial coils. One of the pair of connection portion in this aspect may also have an opening in communication with the through-hole. Furthermore, the core molding member may include a wall portion standing upright at a location facing with each other across the opening. In addition, the core molding member may include an inclined portion formed of a resin material that becomes thin toward

the opening. Moreover, one of the pair of connection portion may include a pair of opposing connection portions which face with each other via a clearance in a direction orthogonal to the connection direction. The other of the pair of connection portion may be disposed at an opposing location between the opposing connection portions, and may be formed with the width equal to or smaller than the clearance between the opposing connection portions. The pair of connection portion may include a tabular portion in the direction orthogonal to each other.

As illustrated in FIG. 16, a restriction portion **629** is formed by a pair of protruding portions **629a** and **629b** provided to the core molding member **6**. The protruding portions **629a** and **629b** is provided between a pair of partial coils **21a** and **22a** attached across the coupling portion **621** so as to protrude from the outer circumference surface. In detail, the protruding portion **629a** protrudes in a C-shape extending in the height direction of the core molding member **6**. As illustrated in FIG. 17, the protruding portion **629a** is provided to a position close to the end surfaces of the partial coils **21a** and **21b**, and the protruding portion **629b** is provided to a position close to the end surfaces of the partial coils **22a** and **22b**. Between the protruding portion **629a** and the protruding portion **629b** is a region filled by the dropped filler. Note that the protruding portion **629a** and **629b** is similarly provided to between the pair of partial coils **21b** and **22b**. The protruding portion **629a** is provided to a position close to the end surfaces of the partial coils **21a** and **21b**, and the protruding portion **629b** is provided to a position close to the end surfaces of the partial coils **22a** and **22b**. Between the protruding portion **629a** and the protruding portion **629b** is a region filled by the dropped filler.

Here, in the casing which houses therein the reactor main body, heat-dissipation effect is improved because heat from the reactor main body is transferred to the casing via the filler. To achieve such heat-dissipation effect, it is preferable that the filler is uniformly filled between the reactor main body and the casing. However, the conductor forming the coil easily deforms even after it is attached to the partial core. When such deformation occurs, region between the partial cores where the filler is filled becomes narrow, and there is a possibility that the filler is not sufficiently filled.

In more detail, the conductor forming the coil easily leans so that the inclination angle relative to the winding direction becomes larger even after it is attached to the partial core. When such leaning of the conductor occurs, a region between the pair of partial coils **21a** and **22a** where the filler is filled becomes narrow. The present aspect can address the problem that a region between the pair of partial coils where the filler is filled becomes narrow. That is, in the present aspect, as illustrated in FIG. 17, even when the conductor of the pair of partial coils **21a** and **22a** leans, since the restriction portion **629** prevents leaning of the conductor from becoming large and restricts the clearance between the partial coils **21a** and **21b**, the region where the filler is filled can be ensured. This function of such a restriction portion **629** is similar for a pair of partial coils **21b** and **22b**.

(6) A communication opening which is in communication with the through-hole and where the core is exposed from the core molding member may be provided to the above connection portion. For example, a reactor according to an aspect of an embodiment may include a core which includes at least a pair of partial cores disposed via a gap, a coil attached to a part of the core, and a core molding member which is formed integrally by a resin material and which covers the pair of partial cores, in which the core molding member includes a coupling portion which is provided

between the pair of partial cores at a location corresponding to the gap, the coupling portion includes a through-hole, and a pair of connection portions which face with each other across the through-hole and which connects a space between the pair of partial cores, the reactor further includes a housing which houses therein the reactor main body having core, the coil, and the core molding member, and a filler molded portion formed of a filler provided between the reactor main body and the housing, and a communication opening which is in communication with the through-hole and where the core is exposed from the core molding member is provided to the connection portion. One of the pair of connection portion may also have an opening in communication with the through-hole. Furthermore, the core molding member may include a wall portion standing upright at a location facing with each other across the opening. In addition, the core molding member may include an inclined portion formed of a resin material that becomes thin toward the opening. Moreover, one of the pair of connection portion may include a pair of opposing connection portions which face with each other via a clearance in a direction orthogonal to the connection direction. The other of the pair of connection portion may be disposed at an opposing location between the opposing connection portions, and may be formed with the width equal to or smaller than the clearance between the opposing connection portions. The pair of connection portion may include a tabular portion in the direction orthogonal to each other.

That is, as illustrated in FIGS. 18(A) and 18(B), an communication opening 630, from which the T-shaped cores 12a and 12b that are the partial cores are exposed, is formed on the inner side surface of the coupling portion 621 facing the through-hole 622. In the example of FIG. 18, the end surfaces of the center protrusions Pa and Pb of the T-shaped cores 12a and 12b are exposed. When the filler is filled, the filler flown into the through-hole 622 contacts with the T-shaped core 12a and 12b via the communication opening 630 inside the through-hole, and forms the filler molded portion R.

Here, in the casing which houses therein the reactor main body, heat-dissipation effect is improved because heat from the reactor main body is transferred to the casing via the filler. However, when the resin material corresponding to the magnetic gap between the partial cores is present, heat from the partial cores in the resin material may not be efficiently transferred to the filler.

In detail, since the coil 20 is directly in contact with the filler molded portion R, the heat is easily transferred to the casing 3 that is the housing via the filler molded portion R, however, since the T-shaped core 12a and 12b that are the pair of partial cores are covered by the core molding member 6 formed of resin material together with the gap, it is difficult for heat to be transferred to the filler molded portion R. In the present aspect, as described above, the problem that heat from the partial cores in the resin material is not efficiently transferred to the filler can be addressed. That is, in the present aspect, since the filler molded portion R directly contacts with the partial cores via the communication opening 630, heat from the core 20 is efficiently transferred to the filler, and the heat-dissipation effect is improved.

 630: communication opening
 R: filler molded portion

What is claimed is:

1. A reactor comprising:
 a core that comprises at least a pair of T-shaped cores, each having a center protrusion, the at least a pair of T-shaped cores being disposed with a gap therebetween;
 a coil attached to a part of the core;
 a core molding member which is formed integrally by a resin material and in which the pair of T-shaped cores are embedded;
 a housing which houses therein a reactor main body comprising the core, the coil and the core molding member; and
 a filler molded portion formed of a filler provided between the reactor main body and the housing,
 wherein:
 the core molding member comprises a coupling portion that is provided between the pair of T-shaped cores at a location corresponding to the gap, and
 the coupling portion is provided with a through-hole filled with the filler, the coupling portion further having a pair of connection portions which face with each other across the through-hole and which connect a space between the pair of T-shaped cores.

19

2. The reactor according to claim 1, wherein:
the core is annular; and
the coupling portion is disposed at an inner-circumference
side of the annular core.
3. The reactor according to claim 1,
a filler molded portion formed of a filler provided between
the reactor main body and the housing,
wherein one of the connection portions is provided with
an opening in communication with the through-hole.
4. The reactor according to claim 3, wherein the connection
portion comprises a wall portion that comprises pieces
standing upright at a location facing each other across the
opening.
5. The reactor according to claim 3, wherein the connection
portion comprises an inclined portion formed of a resin
material that becomes thin toward the opening.
6. The reactor according to claim 1, wherein one of the
pair of connection portions comprises a pair of opposing
connection portions which face with each other via a clearance
in an orthogonal direction to a connection direction.
7. The reactor according to claim 6, wherein the other one of
the pair of connection portions is disposed between the
opposing connection portions so as to face with each other,
and is formed by a width that is equal to or smaller than a
clearance between the opposing connection portions.
8. The reactor according to claim 1, wherein the pair of
connection portions comprises respective tabular portions in
a direction orthogonal to each other.
9. The reactor according to claim 1,
wherein an enlarged portion which a cross-section of a
cross-sectional shape of the through-hole is provided at
one end portion of the through-hole.
10. The reactor according to claim 1,
wherein enlarged portions which are each a cross-section
of a cross-sectional shape of the through-hole are
provided at both of a pair of end portions of the
through-hole.

20

11. The reactor according to claim 3, wherein:
the coil includes a pair of partial coils attached across the
coupling portion, and
a restriction portion which restricts the clearance between
a pair of the partial coils is provided to the core molding
member.
12. The reactor according to claim 3, wherein a communication
opening which is in communication with the
through-hole and where the core is exposed from the core
molding member is provided to the connection portion.
13. A reactor comprising:
a core that comprises at least a pair of partial cores
disposed with a gap therebetween;
a coil attached to a part of the core; and
a core molding member which is formed integrally by a
resin material and which covers the pair of partial
cores,
wherein:
the core molding member comprises a coupling portion
that is provided between the pair of partial cores at a
location corresponding to the gap,
the coupling portion is provided with a through-hole, the
coupling portion further having a pair of connection
portions which face with each other across the through-
hole and which connect a space between the pair of
partial cores,
one of the connection portions comprises a pair of opposing
connection portions which face each other via a
clearance in a direction which is orthogonal to a
connection direction, and
another one of the connection portions is disposed
between the opposing connection portions so as to face
each other, the another one of the connection portions
having a width that is equal to or smaller than the
clearance between the opposing connection portions.

UNITED STATES PATENT AND TRADEMARK OFFICE
CERTIFICATE OF CORRECTION

PATENT NO. : 11,842,836 B2
APPLICATION NO. : 16/962737
DATED : December 12, 2023
INVENTOR(S) : Kotaro Suzuki and Yasuhiro Uekusa

Page 1 of 1

It is certified that error appears in the above-identified patent and that said Letters Patent is hereby corrected as shown below:

In the Claims

Claim 3, Column 19, Lines 6-7, please delete the phrase “a filler molded portion formed of a filler provided between the reactor main body and the housing”.

Claim 7, Column 19, Lines 24-25, please delete the phrase “a clearance” and replace with “the clearance”.
